CLAIM

The ornamental design for a ballpoint pen, as shown and described herein.

DESCRIPTION

FIG. 1 is a perspective view of the ballpoint pen of the present invention;

FIG. 2 is a front view thereof;

FIG. 3 is a rear view thereof;

FIG. 4 is a left side view thereof;

FIG. 5 is a right side view thereof;

FIG. 6 is top view thereof; and,

FIG. 7 is a bottom view thereof.

The broken lines in the figures depict portions of the ball point pen which form no part of the claimed design.
